FAN SYSTEM

Amos C. Bartlett, Braintree, Mass., assignor to
 B. F. Sturtevant Company, Hyde Park, Boston,
 Mass.

Application May 23, 1936, Serial No. 81,455

3 Claims. (Cl. 98—50)

This invention relates to fan systems and relates more particularly to a fan system for the ventilation of mines.

In a mine having a given area to supply with air, it is desirable to circulate a constant volume of air. As shown by "Coal Miner's Pocketbook" published by the McGraw-Hill Book Company, the power required to move the air in a mine varies as the cube of the velocity and volume so 5 10 15

it is always desirable to maintain the velocity and volume of air moved by the fan at the minimum which will satisfy the requirements for ventilation.

The volume of air at a given time in a mine 15 of given area varies with changes in barometric pressure and temperature. When both temperature and pressure change, the change in volume is directly proportional to the change in absolute temperature according to Gay-Lussac's law, and 20 is inversely proportional to the change in absolute pressure according to Mariotti's law. The changes in volume due to changes in pressure and temperature are substantial as shown by the fact that a drop in barometric pressure from 29.5 to 25 29.0 will cause a volume of 1,000,000 cubic feet of air to increase 17,250 cubic feet. Likewise a rise in temperature say from 75° F. to 95° F. will cause a volume of 1,000,000 cubic feet of air to increase 37,400 cubic feet. In a shaft type mine 30 of substantial depth, the above increases in volume would be further increased due to the stack effect.

According to this invention, there is provided for mines, a centrifugal fan with adjustable spin 35 inducing vanes in its inlet. The inlet vanes are adjustable from wide open position where they have substantially no effect upon the air moved by the fan wheel, to closed position where they impart a spin to the air entering the fan wheel 40 which approximates the movement of the wheel so that the wheel has little effect upon the air. This enables the volume of the fan to be varied while driven by a constant speed motor. The inlet vanes are adjusted by a velocity meter 45 mounted in the passage leading to the fan, to maintain a constant volume of air through the passage. The cross-section of the passage is constant so that the velocity meter responds accurately to changes in the volume of air passing it.

50 An object of the invention is to maintain a constant volume of air through a mine of given area.

Another object of the invention is to provide for the ventilation of a mine, a centrifugal fan 55 having adjustable spin inducing vanes in its inlet

and to adjust the vanes to maintain the desired conditions within the mine.

Other objects of the invention will be apparent from the following description taken together with the drawing. 5

The invention will now be described with reference to the drawing of which:

Fig. 1 is a diagrammatic sketch of a shaft mine equipped according to this invention;

Fig. 2 is a diagrammatic view of a fan with 10 controls according to this invention, and

Fig. 3 is a circuit schematic illustrating relay switching for reversing the vane control motor.

Shaft mines are provided with at least two shafts, one for the inlet of the ventilating air 15 and the other for the exhaust of the air. As shown by Fig. 1, it is usual for the hoisting shaft 5 to serve also as the inlet for the ventilating air. The exhaust air passage 6 may also contain stairways for the mines. The fan house 7 over 20 the shaft 6 contains the fan apparatus according to this invention, and mounted within the shaft 6 is the velocity meter 8 which responds to changes in the velocity of the air passing it to adjust the fans as will now be described with 25 reference to Fig. 2.

The fan 9 is preferably similar to the one described in the Patent No. 1,846,863 to H. F. Hagen, with the exception that in the present case, a fan with a single inlet is illustrated. Mounted 30 within the inlet 10 of the fan are the adjustable vanes 20, the functions, arrangement and adjustment of which are identical with those of said patent, and so will not be described in detail here. It is believed to be sufficient to state that 35 the cranks and links, etc., indicated generally by 11 are adjusted by the rotation of the gear 12, corresponding to the gear 48 of said patent. The gear 12 is in turn rotated by the gear 13 mounted in the same shaft as the gear 14 which is rotated 40 through the intermediary of the chain or belt 15 from the motor 16. Rotation of the armature of the motor 16 in one direction adjusts the vanes 20 towards their full open position and rotation of the armature in the other direction adjusts 45 the vanes towards their closed position.

The operation and direction of rotation of the motor 16 are controlled by the relays 17 and 18 which in turn are controlled by the velocity meter 8 as will now be explained. The velocity meter 8 which may be of the type manufactured by the Illinois Testing Laboratories Inc. of Chicago, Illinois, contains the vane 28 in contact with the moving air, the return spring 29, the indicator 25 and contacts 26 and 27. At air velocities appre- 50 55

ciablely above that necessary to give the desired air volume, the indicator 25 is moved against the contact 27 to close a circuit including the solenoid winding of the relay 17 and the electric source 30 to cause the relay 17 to connect the field and armature windings of the motor 16 to the current source 30 to cause the motor 16 to rotate in a direction to adjust the vanes of the fan towards closed position so as to reduce the action 10 of the fan upon the air. The motor 16 will rotate until the indicator 25 leaves the contact 27.

At air velocities appreciably below that necessary to give the desired air volume, the indicator moves against the contact 26 to energize the relay 18 which then closes contacts to connect the armature and field of the motor 16 to the electric source 30 but in reverse relation to each other to cause the motor to run in a reverse direction from that previously described to adjust the inlet vanes towards their open position. The motor will continue to run and adjust the vanes until the circuit established by the indicator 25 and contact 26 is opened when the volume has become restored to that desired.

25 Pressure and temperature responsive instruments could of course be used to control the air flow, but for practical considerations, an instrument such as has been described, which will respond to condition indicating change in volume, 30 is preferred.

Whereas one embodiment of the invention has been described for the purpose of illustration, it should be understood that the invention is not to be limited to the exact arrangement described, 35 as many departures and modifications will suggest themselves to those skilled in the art, after having had access to this disclosure.

What is claimed is:

1. A fan system comprising in combination, means forming a ventilating passage, a fan connected to said passage, a plurality of spin inducing vanes in the inlet to said fan, means for adjusting said vanes for varying the total volume of air moved by said fan, and means responsive to changes in the volume of the air moving through said passage for adjusting said last mentioned means to maintain a constant air volume moved through said passage and delivered by said fan.

2. A fan system comprising in combination, a space to be ventilated, an exhaust fan, means forming an air exhaust passage from said space to said fan, a plurality of spin inducing vanes in the inlet to said fan, means for adjusting said vanes for varying the total volume of air extracted from said space by said fan, and means responsive to changes in the volume in said passage for adjusting said last mentioned means for maintaining a constant air volume through said passage and exhausted by said fan.

3. A fan system comprising in combination, a space to be ventilated, means forming a fresh air passage connecting with said space, means forming an exhaust air passage connecting with said space and the atmosphere, a fan in said exhaust air passage for drawing fresh air through said fresh air passage and for drawing exhaust air from said space and for discharging same into the atmosphere, a plurality of spin inducing vanes in the inlet of said fan, means for adjusting said vanes, and means responsive to changes in the volume of air moving through said exhaust air passage for adjusting said last mentioned means.
